UNITED STATES PATENT OFFICE.

SOLOMON H. GOLDBERG, OF CHICAGO, ILLINOIS, ASSIGNOR TO THE HUMP HAIRPIN MANUFACTURING COMPANY, OF CHICAGO, ILLINOIS, A CORPORATION OF WEST VIRGINIA.

HAIR-PIN.

1,126,752.

Specification of Letters Patent.

Patented Feb. 2, 1915.

Application filed July 16, 1909. Serial No. 507,949.

To all whom it may concern:

Be it known that I, SOLOMON H. GOLDBERG, citizen of the United States, residing in the city of Chicago, county of Cook, 5 State of Illinois, have invented certain new and useful Improvements in Hair-Pins, of which the following is a specification.

This invention relates to improvements in hairpins and refers more particularly to improvements in that type of hairpin heretofore invented by me and patented December 10, 1903, No. 748278.

Among the salient objects of the invention are to provide a construction which is 15 extremely economical in manufacture, and nevertheless durable; and which can be readily formed from a single piece of twisted wire; to provide a construction which is entirely concealed when placed in the hair 20 and which is firmly held in position by means of its peculiar construction; to provide a construction of the above character which permits of ready ingress to the hair without tending to push upwardly through 25 the hair and separate and disarrange the latter; to provide a construction and in general to provide improved details of construction and arrangements in a device of the character referred to.

30 The invention consists in the matters hereinafter described and more particularly pointed out in the appended claims.

In the drawings Figure 1 is a front elevation of my improved device; Fig. 2 is a side 35 view of the same; Fig. 3 is a front elevation of a slightly modified construction.

Referring to the drawings 1, 1 designate the main legs of the hairpin which may or may not be corrugated at their inner ends 40 as shown at 2, 2. Between the legs are secured central confining or inter-locking members 3, 3 which are integrally connected at their inner ends to the respective legs and at their outer ends are joined together 45 by a uniting loop portion 4. The inner ends of the inter-locking members 3 are twisted together by a single twist 5 as shown in Fig. 1 or by a plurality of twists as shown in Fig. 3. Each member 3 is provided inter-

mediate its ends with an offset hump portion 6 these hump portions being of course in register with each other. The loop portion 4 of the inter-locking member is in alinement with the legs 1 *i. e.* lies in the same plane with the latter. It has been 55 found in practice that this is of especial importance for the reason that it prevents the hairpin when inserted in the hair from forcing its way upwardly through the latter; and thus disarranging the coiffure. At 60 the same time the arrangement described is such that the hairpin will always slip easily into the exact position in which the wearer desires to put it. While the details of construction are extremely simple they are 65 nevertheless important in securing the most efficient results. After the hairpin has been inserted in the hair it is held in position by the twisted or corrugated portion in connection with the hump. The straight closed 70 loop performs the additional function of permitting a smooth entry into the hair.

The operation of the device is extremely simple and needs no description.

I claim as my invention:

1. A hairpin formed from a single piece of wire and comprising a pair of outer leg portions, a central leg portion formed by doubling the central portion of said wire and twisted as to its inner end, said central 80 leg having a hump formed in its outer half and terminating in an eye the sides of which lie substantially in the same plane from the apex of the hump to the extremity of the eye.

2. A hairpin formed from a single piece of wire and comprising a pair of outer legs, a central leg formed by doubling the wire centrally, twisted as to its inner end and having a hump between said twisted portion 90 and its outer end, and terminating in an eye, the sides of which lie in substantially straight lines from the apex of the hump to the extremity of the eye.

SOLOMON H. GOLDBERG.
